CLOCK HOUSING

Ben Lerman, Chicago, Ill., assignor to Master-crafters Clock & Radio Company, Chicago, Ill., a corporation of Illinois

Application February 24, 1950, Serial No. 8,101

Term of patent 14 years

(Cl. D42—7)

To all whom it may concern:

Be it known that I, Ben Lerman, a citizen of the United States of America and resident of the city of Chicago, county of Cook, and State of Illinois, have invented a new, original, and ornamental Design for a Clock Housing, of which the following is a specification, reference being had to the accompanying drawing, forming a part thereof.

Fig. 1 is a front elevational view of a clock housing, showing my new design.

Fig. 2 is a top plan view thereof.

Fig. 3 is a side elevational view thereof.

Fig. 4 is a bottom view thereof.

The dominant features of my design are shown in full lines.

I claim:

The ornamental design for a clock housing, substantially as shown and described.

BEN LERMAN.
